UNITED STATES PATENT OFFICE.

ADOLPH S. KLEIN, OF CLEVELAND, OHIO.

REFRIGERATOR.

1,174,256.

Specification of Letters Patent.

Patented Mar. 7, 1916.

Application filed July 18, 1913. Serial No. 779,658.

To all whom it may concern:

Be it known that I, ADOLPH S. KLEIN, a citizen of the United States of America, residing at Cleveland, in the county of Cuyahoga and State of Ohio, have invented certain new and useful Improvements in Refrigerators; and I hereby declare the following to be a full, clear, and exact description of the invention, such as will enable others skilled in the art to which it pertains to make and use the same.

This invention relates to improvements in refrigerators, and pertains more especially to a portable refrigerator having two provision-chambers, and a metal tank for receiving the refrigerant between said chambers.

The object of this invention is to have said tank slidable from and to its place within the refrigerator and supported by simple, suitable and efficient means from the top of the refrigerator.

With this object in view, this invention consists of certain features of construction and combination and arrangement of parts, hereinafter described, pointed out in the claim, and illustrated in the accompanying drawings.

In said drawings, Figure 1 is a vertical longitudinal section of a portable refrigerator embodying my invention, the section being taken through the tank G in close proximity to the outlet 15 of the tank. Fig. 2 is a horizontal section on line 2—2, Fig. 1, looking downwardly. Fig. 3 is a horizontal section on line 3—3, Fig. 1, looking downwardly. Fig. 4 is a transverse vertical section on line 4—4, Fig. 1, looking in the direction indicated by the arrow.

Referring to said drawings, A indicates the suitably spaced front and back upright walls of the casing of my improved refrigerator, and B, Fig. 1, represents the upright end walls of said casing. Said casing also comprises a bottom C on which the walls A and B rest and also comprises a top D extending over and resting on the top edges of said walls.

Two provision-chambers E are shown formed internally of opposite end-positions

respectively of the casing of the refrigerator illustrated and extend between the front and back walls A and from the bottom C to the top D. Centrally between the provision-chambers E is arranged a metal tank G for receiving a suitable refrigerant, such, for instance, as crushed ice and salt for the production of brine. The tank G has its upper portion rectangular in cross-section, and one of the walls A of the casing is provided with an opening a having the dimensions and arrangement required to render the tank capable of being removed through said opening. That is, the casing of the refrigerator is provided in one upright wall A thereof with an opening a extending laterally through said wall, and the tank G extends between said opening in said wall and the opposite upright wall of the casing and is movable endwise through said opening. The tank has a top 8 and is provided with a non-conducting or insulating closure g which closes said opening a and prevents exposure of the tank at said opening to the external atmosphere. The closure g is rigidly secured to the tank G in any approved manner.

The casing of the refrigerator is provided, next below the top D and above the tank G, with a substantially horizontally arranged section H which extends between the walls A and consequently longitudinally of the tank. The section H is secured to said casing in any approved manner.

Two substantially horizontally extending and substantially parallel bars I are arranged at and longitudinally of opposite side edges respectively of the section H and consequently extend longitudinally of the tank G. The bars I are provided with laterally and outwardly projecting substantially horizontally arranged flanges 10 which extend longitudinally of the bars and are arranged over and spaced somewhat from the top 8 of the tank G which is provided with two metal bars J arranged adjacent the top and at opposite sides respectively of the tank. The bars J are substantially parallel with the bars I and consequently extend longitudinally of the tank G. The bars J are provided with laterally and

inwardly projecting substantially horizontally arranged flanges 12 extending longitudinally of said bars and resting on the flanges 10 of the bars I. It will be observed that the bars J are shiftable endwise of the bars I, and that the tank G is secured to the bars J in any approved manner and consequently said tank is suspended from the bars I in such a manner as to render said tank free to be shifted endwise through the opening a, and the closure g carried by said tank is provided at the outer side of its upper portion with a pull or handle 13.

The tank G is provided in the forward portion of its top 8 and in proximity to the closure g with a charging aperture 14 closed by a removable lid K. Upon removing the lid K access is had to the interior of the tank which is charged with ice and salt through said aperture.

The tank G is provided adjacent the lower extremity of its end which is adjacent to the closure g with an outlet 15 and has its bottom substantially V-shaped in cross-section, as shown in Fig. 1, and sloping upwardly from said outlet toward the opposite end of the tank. The closure g is provided with means such, for instance, as a valved faucet L, for controlling the flow of brine or water through said outlet, but of course brine, being used as a refrigerant, is permitted to accumulate in the tank G. The faucet L is applied in any approved manner and connects with the tank G. The joint between the inner end of the faucet and said tank is of course rendered fluid-tight in any approved manner.

Two upright air passageways 16 are arranged at opposite sides respectively of the tank G between said tank and the provision-chambers E. That is, between each side of the tank G and the adjacent provision-chamber is formed an upright air-conducting passageway 16 and said side of said tank forms one side wall of said passageway, whereas the other side wall of said passageway is formed by an upright partition P which also forms the adjacent side wall of said chamber. Said partition extends between the walls A of the casing of the refrigerator but is spaced at its upper and lower ends from the top and bottom of said casing so that the passageway 16 formed between said partition and the tank is in communication at said ends of the partition with the adjacent provision-chamber. Said partition is supported from the walls A but removable upwardly and preferably each of said walls is provided at the lower end of said partition with a bracket R instrumental in supporting said partition, which bracket is secured to the respective wall in any approved manner and is provided (see Fig. 1) with a seat 17 for the bottom edge of said

partition and has two members r arranged at opposite sides respectively and preventing lateral displacement of said partition, and each of said walls is also provided adjacent the upper portion of said partition with a guide for the partition, which guide consists of a plate T secured to said wall in any approved manner and having two flanges t overlapping opposite sides respectively and preventing lateral displacement of the partition. Each partition P is preferably provided in its lower portion with perforations 18.

By the construction hereinbefore described it will be observed that air within the provision-chambers, upon ascending, as its temperature rises, can pass to and over the partitions P and into contact with the tank G and by said contact has its temperature lowered and thereupon descends within the air-passageways 16. It will also be observed that the lower portion of the tank G, being substantially V-shaped in cross-section as hereinbefore described operates to guide cold air into the lower portions of the provision-chambers.

The top wall D of the casing of my improved refrigerator is provided above each provision-chamber with an opening d affording access to said chamber, which opening is closed by a suitably applied door or closure Q which closes said opening, and said opening d extends from over said chamber to and over the adjacent air-conducting passageway 16 and consequently over and across the top edge of the partition P between said passageway and said chamber. An opening d is shown in dotted lines Fig. 4, and it will be observed upon reference to Figs. 1 and 4 that said opening has the arrangement and dimensions required to render the adjacent partition P, upon the removal of the closure occupying said opening, removable upwardly from within the refrigerator for cleaning purposes. It is obvious that the removability of the tank G endwise through one of the upright walls of the casing of the refrigerator and the removability of the partitions P upwardly from within said casing renders the refrigerator capable of being easily kept in a clean condition.

What I claim is:—

In a refrigerator, a refrigerant-receiving tank having its upper portion rectangular and provided at its upper end with two substantially parallel laterally spaced bars which extend longitudinally of the tank and have flanges extending longitudinally of the bars and arranged over and spaced from the tank; a section supported beneath the top of the refrigerator and arranged substantially horizontally over and extending longitudinally of and spaced from the tank, and two bars arranged at and longitudinally of oppo-

site side edges respectively of and secured to said section and having laterally and outwardly projecting flanges which extend longitudinally of said bars and project under the flanges of and form supports for the first-mentioned bars and connected tank.

5 In testimony whereof I sign the foregoing

specification, in the presence of two witnesses.

ADOLPH S. KLEIN.
